UNITED STATES PATENT OFFICE

WILLIAM C. KRABIEL, OF WINTERSSET, IOWA

FURRING STRIP ANCHOR AND PROCESS FOR USING THE SAME

Application filed August 18, 1927. Serial No. 213,833.

The object of my invention is to provide a furring strip anchor of very simple and durable construction, which can be made and sold at a low cost and to likewise set forth and 5 provide a method of using the anchor.

More particularly, it is my object to provide a furring strip, which can be conveniently and easily adapted to a wooden form in such manner as to leave anchoring elements projecting therefrom and adapted to 10 be received in concrete or other plastic material for holding the anchor, the means for fastening said device to the form being such as to permit the convenient and easy removal 15 of the wood form members.

Still another purpose is to provide in such a device means for securing to the furring strips, which means can be folded out of the way until the time comes to install the furring strips.

With these and other objects in view, my invention consists in the construction, arrangement and combination of the various parts of my furring strip anchor, whereby the 25 objects contemplated are attained, as hereininafter more fully set forth, pointed out in my claims, and illustrated in the accompanying drawings, in which:

Figure 1 is a perspective view of a furring 30 strip anchor embodying my invention.

Figure 2 is a vertical, sectional view through a portion of a metal form with a wooden form base equipped with a furring strip anchor embodying my invention.

Figure 3 is a detail, sectional view taken 35 on the line 3—3 of Figure 2.

Figure 4 is a sectional view similar to that of Figure 2, showing the manner of installing my furring strip in connection with web reinforcing or clay tile flat ceiling construction.

Figure 5 is a view similar to that of Figure 4, showing the wooden form base removed.

Figure 6 is a similar view showing the 45 parts after the fastening nails have been clipped off.

Figure 7 shows the anchor with the proper members embedded in the concrete and the furring strips installed; and

Figure 8 is a sectional view through the

furring strip anchor showing the registering holes therein.

It is frequently desirable in building ceilings of the kind using plastic material to provide furring strips on the underside of the 55 ceiling for the attachment of lath or other finishing material.

Where the ceiling is made of plastic material, it is often difficult to attach the furring strips.

The object of my invention is to provide a convenient anchor for this purpose.

In the accompanying drawings in Figure 2, I have shown a fragment of the forms used for providing a concrete or plastic material 65 ceiling, which, of course, may also serve as the floor for the room above.

In Figures 2 and 3, I have shown the metal form members indicated by the reference numeral 10. These form members have generally the shape of inverted pans with projecting flanges 12 at the their lower edges. The portions 12 rest upon wooden form members 14. Concrete is poured over the form members 10 in the form of a thick slab, the upper surface of which is flat, and the lower surface of which is ribbed. The ribs are formed between the successive pans 10.

In order to provide means for securing the furring strips to the slab thus formed, I 80 use my improved furring strip anchor of the kind shown in Figure 1.

This anchor is preferably made of sheet metal or wire having the central, horizontal member 16 at the ends of which are upwardly projecting portions 17.

At their upper ends, the metal is bent outwardly and downwardly from the members 17, forming the downwardly extending portions 18 immediately adjacent to and parallel 90 with the portions 17. I preferably punch the portions 17 and 18, as at 20, to form the projecting anchor devices 22.

In the manufacture of my furring anchors in the factory, the lower ends of the members 18 are bent to rest in planes adjacent to and parallel with the members 16 and overlapping each other, forming the furring strip engaging ears 24.

The members 16 and 24 are provided with

holes 26 and 28, which register when the parts are in their completed form, as shown in Figures 1 and 8.

In installing the furring anchors in connection with the forms, pointed members, such for instance as nails 30, are inserted through the holes 26 and 28 from between the anchoring legs, formed by the members 17 and 18, and are driven into the wooden form member 14 for instance.

For convenience in reference to the furring strip anchor, I have referred to the members 17 and 18, as the anchoring legs A, to the member 16, as the central member B, and to the members 24 as the furring strip ears C.

In Figure 4, I have shown my furring strip anchor installed in connection with another type of form used for clay tile flat ceiling construction with web reinforcing.

In this structure, the clay tile 32 is supported on the wooden form members 34 in such manner that the slab 36 may be poured and will have a flat upper surface, and will have the downwardly projecting ribs 36a formed between the rows of tile 32.

When such a form is used, the furring anchor is fastened to the wood form member 34 in the same way.

In Figure 5, I have shown the anchor in the form of the device shown in Figure 4, after the concrete slab 36 has hardened and the wood form member has been pulled away from the pointed members 30.

It is not desirable where workmen are on the job to have the pointed members 30 projecting, as shown in Figure 5, and one valuable feature of my present anchor arises from the fact that these members 30 may be clipped off to leave no projecting parts as shown in Figure 6.

The furring strip engaging ears 24 will then be folded up under the member 16 adjacent to each other and will be out of the way and not subject to distortion and injury while other work is being done about the building.

Then when the time arrives to install the furring strips, the members 24 forming the furring strip receiving ears C are straightened out until they extend away from the member 16.

It will be understood that these anchoring devices are installed in rows, so that the furring strip 38 may be inserted between a series of pairs of ears C, as shown in Figure 7, whereupon nails 40 may be driven through the holes 28 into the furring strip 38 for rigidly anchoring the furring strip in position.

Such a device has a number of important advantages.

It is simple and cheap. It is readily and easily installed. It does not interfere with the pouring of the concrete slab. It furnishes an adequate anchor. There are no projecting parts after the slab has hardened,

which may be injured or distorted or may cause injury or inconvenience to the workmen. It may be used either on side walls or ceilings.

I claim as my invention:

1. In a furring anchor, an anchoring element having a pair of stiff legs and a member for connecting them and holding them in spaced relation, a pair of anchoring ears connected at spaced points with said element and adapted to normally lie in superposed relation to said member and each other and to be moved to spaced position extending away from said member, said member and ears having holes which register when such member and ears are in superposed position and a headed removable securing device projected through said holes for supporting the anchor relative to a form.

2. A process for using a furring strip anchor as herein disclosed having overlapping furring strip supporting ears, comprising the securing of the anchor by fastening devices to a form, the introduction of a plastic body into the form whereby the anchoring legs of the anchor are imbedded in the plastic body and the body portion of the anchor is arranged at the surface of the plastic body with the furring strip supporting ears in non-projecting position, the clipping of said fastening devices to permit the bending of said ears and the bending of said ears to a projecting position whereby a furring strip may be secured between them and thereby supported.

Des Moines, Iowa, July 25, 1927.

WILLIAM C. KRABIEL.
